UNITED STATES PATENT OFFICE.

GEORGE B. FRALEY, OF SAN FRANCISCO, CALIFORNIA.

DESIGN FOR A FRAME FOR ELECTRIC DYNAMOS.

SPECIFICATION forming part of Design No. 21,906, dated October 18, 1892.

Application filed August 16, 1892. Serial No. 443,267. Term of patent 3½ years.

To all whom it may concern:

Be it known that I, GEORGE B. FRALEY, a citizen of the United States, residing in the city and county of San Francisco, State of California, have invented and produced a new and original Design for the Frame of an Electric Dynamo, of which the following is a specification, reference being had to the accompanying drawing, showing a part thereof.

10 The leading feature of my design consists of the segmental pole-pieces, having grooves or channels made in their outer edges, and an ornamental standard or support with bars extending horizontally from the top and bottom and connecting, respectively, with the upper and lower segments.

15

A A are the pole-pieces, which are in the form of segments of circles, having a rounded contour of the outer faces and segmental grooves or channels B made in these faces. 20 C C are bars extending from the rear of these segmental pole-pieces to an ornamental standard D, to which they are united, respectively, at top and bottom, the whole forming an ornamental device. 25

What I claim is—

The design for the frame of an electric dynamo, substantially as herein described.

GEORGE B. FRALEY.

Witnesses:

S. H. NOURSE,
J. A. BAYLESS.
